(57) **CLAIM**

I claim, the ornamental design for a toe valgus orthotic device, as shown and described.

DESCRIPTION

FIG. 1 is a front perspective view of a toe valgus orthotic device design showing my new design.

FIG. 2 is a rear perspective view of the toe valgus orthotic device.

FIG. 3 is a front view of the toe valgus orthotic device.

FIG. 4 is a rear view of the toe valgus orthotic device.

FIG. 5 is a left side view of the toe valgus orthotic device.

FIG. 6 is a right side view of the toe valgus orthotic device.

FIG. 7 is a top view of the toe valgus orthotic device; and,

FIG. 8 is a bottom view of the toe valgus orthotic device.

Any shading and cross-hatching are not features of the design but are utilized to illustrate the surface contours of the toe valgus orthotic device design in the drawings.
